UNITED STATES PATENT OFFICE.

ALBERT R. BETTS, OF CINCINNATI, OHIO, ASSIGNOR TO THE CINCINNATI COFFIN COMPANY, OF SAME PLACE.

DESIGN FOR A CASKET-PLATE.

SPECIFICATION forming part of Design No. 32,551, dated April 17, 1900.

Application filed February 21, 1900. Serial No. 6,115. Term of patent 7 years.

To all whom it may concern:

Be it known that I, ALBERT R. BETTS, a citizen of the United States, and a resident of the city of Cincinnati, in the county of Hamilton and State of Ohio, have invented and produced a new and original Design for Casket-Plates, of which the following is a specification, reference being had to the accompanying drawings, forming part thereof.

10 Figure 1 is a plan view of a casket-plate, showing my new design. Fig. 2 is an edge view of either that edge of the design which faces toward the bottom of the plate or that edge which faces toward the top of the plate.

15 As shown in the drawings, the leading or material feature of my design consists of a casket-plate having a border whose sides and

ends have a series of ribs A, separated by valleys or depressions B. There is a series of these ribs at each side and a series at each 20 end of the plate P. At each corner of the border is an ornamental escutcheon D.

Having described my invention, what I claim as new, and desire to secure by Letters Patent, is—

25 The design for a casket-plate, as herein shown and described.

In testimony whereof I have signed my name to this specification in the presence of two subscribing witnesses.

ALBERT R. BETTS.

Witnesses:

W. M. H. PUGH,
K. SMITH.
